US00D560280S

(12) **United States Design Patent** (10) Patent No.: **US D560,280 S**
(45) Date of Patent: ** Jan. 22, 2008

(54) **MULTIPLE THERAPY DELIVERY
PLATFORM DEVICE**

(75) Inventors: **Thomas R. Skwarek**, Shoreview, MN (US); **Mark A. Christopherson**, Shoreview, MN (US)

(73) Assignee: **Medtronic, Inc.**, Minneapolis, MN (US)

(**) Term: **14 Years**

(21) Appl. No.: **29/289,391**

(22) Filed: **Jul. 18, 2007**

(57) **CLAIM**

The ornamental design for multiple therapy delivery platform device, as shown and described.

DESCRIPTION

FIG. 1 is a perspective view of a multiple therapy delivery platform device with the screen open showing our new design;

FIG. 2 is a front view thereof;

FIG. 3 is a rear view thereof;

FIG. 4 is a bottom view thereof;

FIG. 5 is a left side view thereof;

FIG. 6 is a right side view thereof; and,

FIG. 7 is a top view thereof.

The broken lines are for illustrative purposes only and form no part of the claimed design.
